[57] CLAIM

The ornamental design for a cabinet drawer guide assembly, as shown and described.

DESCRIPTION

FIG. 1 is a bottom plan view of a cabinet drawer guide assembly embodying our design in the closed position; FIG. 2 is a top plan view of the assembly of FIG. 1; FIG. 3 is a left side elevational view of the assembly of FIG. 2, the right side being a mirror image thereof;

FIG. 4 is a rear elevational view of the assembly of FIG. 2; FIG. 5 is a front elevational view of the assembly of FIG. 2; FIG. 6 is a cross-sectional view of the assembly along lines 6—6 of FIG. 1 and FIG. 7;

FIG. 7 is a top plan view of the rail of the assembly removed from the guide and shown separately for completeness of illustration; and,

FIG. 8 is a bottom plan view of the guide of the assembly with the rail removed and shown separately for completeness of illustration.
